UNITED STATES PATENT OFFICE.

CAMPBELL P. HIGGINS, OF ROSELLE, NEW JERSEY, ASSIGNOR TO THE BABCOCK & WILCOX COMPANY, OF BAYONNE, NEW JERSEY, A CORPORATION OF NEW JERSEY.

MACHINE FOR FORMING SEAMLESS TUBES.

961,128.

Specification of Letters Patent. Patented June 14, 1910.

Application filed September 21, 1906. Serial No. 335,668.

To all whom it may concern:

Be it known that I, CAMPBELL P. HIGGINS, a citizen of the United States, residing at Roselle, in the county of Union and State of New Jersey, have invented certain new and useful Improvements in Machines for Forming Seamless Tubes, of which the following is a specification, reference being had therein to the accompanying drawing.

10 This invention relates to improvements in mandrels employed in forming seamless tubes, and is intended to be used in conjunction with coöperating dies and operated by a hydraulic press or other power device.

15 The main object of the invention is to provide a mandrel that will expand and retain its size while in use and under pressure, and will readily retract when the pressure is relieved or when the movement of its parts 20 is reversed, so that the mandrel can easily be withdrawn from the tube.

Another object of the invention is to provide a mandrel that can be readily adapted for use in different sizes or diameters.

25 The invention comprises a mandrel having a continuous core provided with a series of conical or otherwise tapered surfaces, having holes made through each cone of the core. Through these holes cross-pins are 30 passed having permanent and detachable heads that secure to the core movable segmental sections that have their inner faces coned to contact with the conical surfaces of the core, and the sections are placed end 35 to end so as to make practically a continuous shaft. These sections are provided with slots registering with the holes in the core. The holes in the core are made in the proper place to correspond to the diameter of the 40 tube to be formed, so that when pressure is placed on the core the sections expand until the desired size is reached. When the movement of the core is reversed by a release of the pressure, or otherwise, the sections retract, which makes the mandrel smaller than 45 the inside of the tube, and can, therefore, be easily withdrawn. In adapting the mandrel to a different diameter, the movable sections and cross-pins are replaced by others of a size corresponding to a desired 50 diameter.

In the accompanying drawings, Figure 1 is a sectional elevation showing the sections expanded. Fig. 2 is a sectional end elevation through line 4—4 of Fig. 1, showing

the cross-pins and clearance between the sections. Fig. 3 is a sectional elevation showing the mandrel retracted, and sections loose in the tubes.

Referring to the drawings, a core is provided with a plurality of conical surfaces 2 and 3. The core has holes 5 and 6 to fit the cross-pins 7 and 8, which have heads 9 and 10, the head 10 being formed integral and the head 10 riveted to the pin. The 60 cross-pins 6 and 7 extend through sections 12 with their inner faces 13 and 13^a coned to coöperate with the contracting surfaces of the core.

The conical surfaces of the core and coöperating segmental sections, serving to spread the section in the operation of expanding the mandrel, may be made of a greater or less degree of inclination to regulate the speed or amount of movement or 75 bearing of the sections as required.

The cross-pins fit into longitudinal slots 14, cut in the sections 12; the said slots are also provided with recesses 15, to accommodate the heads of the cross-pins which keep 80 the sections assembled on the core. The sections on the end of the mandrel have one end 16 rounded in order to facilitate more effectively the forming operation through the die. The sections being placed end to 85 end form practically a continuous shaft. The clearance spaces 19 (Fig. 2) between the sections 12 are made sufficiently large and are so arranged that the mandrel expands to full size when the work is being pressed 90 through the die. In Fig. 1 the mandrel is shown in connection with a die block 24.

In operation the die block 24 is drawn to one side and a tube having one solid end is placed on the mandrel. When the end of the mandrel is pressed against the solid end of the tube, as shown in Fig. 1, the sections and cross-pins are arranged to permit the mandrel to expand to its full size. The mandrel is then forced upward carrying the 100 tube with it through the die, as also shown in Fig. 1. When the mandrel has pressed the tube through the die, the movement of the parts of the mandrel is reversed and the outer sections retract, as shown in Fig. 3, 105 which make the mandrel smaller than the tube, and can, therefore, be easily withdrawn, leaving the reduced and lengthened tube above the press. The tube is then removed from the press.

This mandrel is adaptable for use with co-operating dies or formers in various operations of drawing or pressing, like, for example, producing seamless tubes with parallel or tapered sides from a circular metal plate or other blank form.

What I claim and desire to secure by Letters-Patent is:—

1. A mandrel comprising a continuous core made up of a series of conical sections, segmental sections having faces corresponding to the core sections and surrounding the core, said segmental sections having openings therein in alinement with openings in the core, and pins passing through said openings whereby the segmental sections are movably connected to the core.

2. A mandrel comprising a continuous core made up of a series of conical sections, segmental sections surrounding said core and having tapered faces co-operating with the tapered surfaces of the core, and cross pins connecting the segmental sections to the core whereby said core and sections are movable relatively to each other in the direction of the taper.

3. A mandrel comprising a continuous core made up of a series of cones arranged longitudinally and successively, surrounding segmental sections having faces inclined to co-operate with the contacting surfaces of the core and forming a substantially continuous outer bearing surface, said cones forming a complete circumferential support for said segments, and means for connecting said sections with the core to permit of longitudinal and lateral movement of the segmental sections.

4. A mandrel comprising a core formed of a plurality of longitudinally arranged tapered members, segmental sections laterally movable relatively thereto mounted upon and surrounding said members and arranged end to end, the front end of said sections being cut away to receive the enlarged end of an adjacent core member.

5. A mandrel comprising a continuous core formed of a plurality of cones, the end of one cone abutting the end of an adjacent cone, segmental sections surrounding each of said cones and forming a substantially continuous outer bearing surface, and means for connecting said sections to the adjacent core members to permit the longitudinal movement of the core and the lateral movement of the segmental sections, said cones forming a

complete circumferential support for said segments.

6. A mandrel comprising a continuous core having a plurality of conical surfaces thereon, segmental sections surrounding said surfaces and having inner faces which co-operate with the conical surfaces of the core and forming a substantially continuous outer bearing surface, the conical surfaces of the core acting by the longitudinal movement to expand the sections outwardly and permit the sections to retract upon a reverse movement of the core, and means movably connecting said sections with the core, said conical surfaces forming a complete circumferential support for said segmental sections.

7. A mandrel comprising a core made up of a series of conical sections, and segmental sections having correspondingly tapered faces and surrounding and supported wholly on said core, and holding means consisting of pins carried by the core and projecting into slots in the segmental sections to permit a relative movement between the core and sections.

8. A mandrel comprising a core made up of a series of conical sections, and having pins projecting laterally therefrom, and segmental sections having correspondingly tapered faces and surrounding said core and having longitudinal slots therein to receive the ends of said pins to permit a relative movement between the core and sections.

9. A mandrel comprising a continuous core having a series of conical sections each of which has a transverse opening therethrough, segments having their inner faces tapered and contacting with the corresponding surfaces of the core, said segments having slots registering with the openings in the core, and pins extending through said openings into the corresponding slots.

10. A mandrel comprising a core made up of a series of conical sections each of which has pins projecting therefrom, and segments arranged end to end and surrounding the conical sections, said segments having their inner faces tapered and bearing upon a corresponding conical section and longitudinal slots to receive the ends of said pins.

In testimony whereof I affix my signature in presence of two witnesses.

CAMPBELL P. HIGGINS.
